Primary Examiner — Dominic V Simone(74) Attorney, Agent, or Firm — Banner & Witcoff, Ltd.(57) CLAIM

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

A grayscale photographic area is shown in the drawings. The broken lines immediately adjacent to the photographic area represent unclaimed boundaries of the design. The eight unshaded regions within the photographic area that are demarcated by broken lines represent unclaimed subject matter and form no part of the claimed design. The broken lines showing the remainder of the shoe represent unclaimed subject matter and form no part of the claimed design.
